BONING

Marcus Schwartz, Flushing, N. Y., assignor to S. & S. Industries, Inc., New York, N. Y., a corporation

Application May 9, 1957, Serial No. 658,087

1 Claim. (Cl. 2—257)

This invention relates to boning which is generally used in ladies' garments for stiffening and/or shaping.

Broadly, it is an object of the invention to provide terminals for boning for garments, namely, brassieres, 15 girdles, corsets and the like, which have a desired and predetermined degree of flexibility and through which a machine sewing needle can pass rapidly and easily without breakage.

More particularly, it is an object of the invention to attach to one or both ends of a garment boning consisting of wire, flat steel, or the like, a flexible plastic terminal preferably of polyethylene, or the like, through which a machine sewing needle can pass without loss of speed or breakage so that such terminals will extend the complete length of the pocket in which the garment stay is housed.

At the present time, garment boning is made of spiral or bent wire or flat steel containing metal caps or tips to avoid sharp ends on the boning. Such caps, tips or terminals have several marked disadvantages. The boning so tipped extends only between the upper and lower stitching lines which are usually $\frac{3}{8}$ " or $\frac{1}{2}$ " from each end of the garment. This boning length is now determined because the lines of stitching which run parallel to the ends must not pass over the boning since the machine sewing needle would break. Thus, the portion of the garment between the ends of the boning and the garment, having no support, rolls or curls over causing discomfort to the wearer and in time, tearing of the garment at each end of the boning pocket. The end of the boning is rigid and, therefore, hard to the skin of the wearer. The boning shifts somewhat in the boning pocket since the width of the pocket is not always the same width as the boning.

I have, therefore, provided plastic terminals or tips for garment boning which are made so that the boning is practically the full length of the boning pocket, that is from the very top of the garment to the opposite end, and through which the machine sewing needle can easily and rapidly pass so that not only is the garment boning anchored in the pocket by the sewing thread but production is accelerated. Furthermore, the terminals or tips have a desirable degree of flexibility which permits movement of the body without discomfort while the garment is supported to the very ends by the boning. It has been also found that the ends of the boning pockets are not as readily worn and susceptible to tearing as is the case with boning which has metal terminals or tips.

The garment industry as a whole has been continuously seeking improvements in boning and methods for tipping same. My invention is considered to be a distinct advance in the art. My tips or terminals provide a flexible, smooth and appropriately contoured plastic tip which is molded-on, or secured intimately to the boning ends, the tip extending beyond the end of the boning approximately $\frac{1}{2}$ " or whatever extension may be required to permit stitching through the tip thus sewing the boning and anchoring it directly within the garment.

Extensive analytical engineering and laboratory test work has been made to determine the type of plastic, and

the grade which would be optimum for the intended usage. The most critical properties of the required material were stiffness modulus, tensile strength, heat resistance, and elongation. The plastic must also be soft enough to permit sewing therethrough.

For a fuller understanding of the nature and objects of the invention, reference is had to the following details of construction in connection with the accompanying drawings, in which:

10 Fig. 1 is a greatly enlarged plan view of one end of one form of metal wire garment stay.

Fig. 2 is a side or edge view of the end of the stay as shown in Fig. 1.

Fig. 3 is an enlarged plan view of one end of another form of metal wire garment stay.

Fig. 4 is an enlarged plan view of one end of a garment stay of flat steel.

Fig. 5 is a plastic garment stay terminal, partly broken away, which can be slipped onto the end of a wire or flat steel garment stay and attached thereto.

Fig. 6 is a sectional view taken through line 6—6 of Fig. 5.

Fig. 7 is a plan view of a portion of the inside of a garment, showing the upper end of a garment stay presently in use, and showing the end extending to the stitching line, the garment stay pocket being partly broken away.

Fig. 8 is a sectional view taken through line 8—8 of Fig. 7.

30 Fig. 9 is a plan view of a portion of the inside of a garment, showing the upper end of the improved instant garment stay and showing the end extending to practically the very edge of the garment, the garment stay pocket being partly broken away.

35 Fig. 10 is a sectional view taken through line 10—10 of Fig. 9.

Referring to the drawing, numeral 20 represents one type of bent wire garment boning presently in use, the 40 ends of which are generally capped or tipped with rigid metal terminals 21, shown in Fig. 7. Garment boning such as shown, is inserted in pockets or terminals 22 formed in the garment by parallel lines of stitching 23. The edges 24 of the garment are formed by turning back 45 the fabric upon itself and stitching a line of stitching 25 parallel to the outer edge, generally about one-half inch from the edge. Garments, such as brassieres, girdles, corsets, and the like, which employ the use of boning, are sewn in large production and time is a big factor in 50 this competitive trade. At the present time, the type of garment boning capped by tips 21, as shown in Fig. 7, are of a length to extend between the upper and lower rows of stitching 25, leaving a soft, bendable or foldable portion of the garment between the stitching 25 and the outer edge 24. This soft portion, if on a brassiere or girdle, will curl and bend, as shown in Fig. 8, making it 55 uncomfortable for the wearer and failing to provide the necessary support at the upper and lower portions of the garment. The reason for not extending the boning shown 60 in Figs. 7 and 8 to the very ends of the garment is that the sewing machine needle would break if it struck the metal cap or terminal 21 or the wire 20 in making stitching line 25. I have, therefore, provided an improved cap tip, or terminal 26, made of a soft, flexible plastic, 65 such as polyethylene or like material which can be easily pierced by a sewing machine needle without breaking and provide additional desirable characteristics for use in garments of the type heretofore mentioned.

Various tests were made to determine the best plastic 70 material for needle penetration. By using a .050 diameter hardened, sharp needle, unthreaded, test results show polyethylene to be an optimum choice. This is undoubt-

edly a result of the combination of softness of material and low coefficient of friction values. The tests were made on a Dillon Tensometer equipped with a special proportional beam.

PENETRATION LOADS

[Sheet thickness, .010—all tests.]

Several plastics can be selected which will satisfy the general requirements, but laboratory and application tests show that a low density polyethylene is most applicable. This is a semi-rigid type of polyethylene produced by polymerization using an oxygen catalyst at high pressures and temperatures. Characteristics of low density polyethylene is the very low inherent coefficient of friction and the fact that it is chemically inert and does not react or degenerate in the presence of mineral or aliphatic acids, soaps, detergents, aqueous salt solutions, or similar compounds. It is also very low in fluid permeability, thus making it highly resistant to water absorption and, therefore, dimensionally stable under all normal conditions of usage. The following is the characteristic range of principal physical properties of the low density polyethylene group:

Density (S. G.)	0.91-0.93
Hardness—Shore	40-50
Stiffness modulus—p. s. i.	10,000-25,000
Tensile strength—p. s. i.	1500-2000
Elongation—percent	200-550
Heat resistance ° F.	212

A specific grade has been selected within the group spread above mentioned, that is soft enough to completely avoid any abrading action against the cloth of the garment. It is also sufficiently flexible to permit the tip extension to be repeatedly at 90° to the axis of the boning without mechanical rupture or fatigue and without taking a set in the direction of banding.

The currently used steel boning with a characteristic crimped metal cap inherently causes one of two possible detrimental effects; one, if the garment designer arranges for the boning to extend to the outline edge of the garment, or completely fill the cloth tunnel or pocket for support purposes, it will require interruptions in sewing of the garment as each seam crosses a bone, whereas my plastic tip with tab extension permits continuous seaming, or stitching and in the aggregate, permit important cost savings by reduction of labor input. The cost of interruption of sewing is important enough to cause some designers to use a shorter piece of boning than normally necessary so that it will not extend to end of garment or into seam line. This permits unsupported edges of garment to roll or curl in actual wear. The use of a plastic sewing tip or tab will permit the designer to obtain full length support without a cost penalty; and two, the other basic difficulty currently experienced is a function of

subsequent shrinkage of the garment fabric. For proper fit the boning comes to the garment edge or tunnel end, but, after the garment has been washed several times, the fabric shrinks but the boning with a metal cap does not and consequently high end stresses are imposed on the metal boning unit causing the end of the boning to break through the garment. This is, obviously, destructive to the garment and, if protrusion is on the inside of the garment it can be painful and injurious to the wearer. With my plastic boning, however, when end pressures are applied, the plastic material is such that it cannot abrade or pierce the fabric.

To prove this fact engineering tests were performed to determine the abrasion on cloth of my plastic tip and a boning with a metal tip. Holding the boning in vertical position, the tip in contact with a thin fabric, 1.5 lbs. loading on the tip and the boning being moved back and forth in contact with the thin fabric, one traverse in either straight line direction was tabulated as a cycle with the following results:

Type	Test No.	Number of Cycles To Cut Through Fabric
Metal Cap	1	102
	2	140
	3	114
	4	110
	5	119
Polyethylene	1	
	2	
	3	(1)
	4	
	5	

¹ No evidence of fabric failure after 500 cycles. The plastic wears slightly instead of fabric failure.

Referring to Fig. 1, the terminal or cap 26 of flexible plastic is preferably molded directly onto each end of wire 20' so that a good portion, possibly one-half or a little less, attaches itself to the wire 20' with the upper portion 27 free to flex or "give" when a force is applied, such as the body of the wearer of the garment containing the boning. The flexibility of portion 27 must be such that it will bend or curve without creating too great a force upon the body and still provide a certain degree of rigidity to gently support the end portion of the garment.

The following tests were established and conducted to determine the relative resistance to bending of the plastic tips as compared with the conventional metal ends. The comparison gave a direct measure of the relative reactive forces, imposed in actual use, which tend to force the ends of boning through the garment material to cause abrasion and ultimate fabric failure as well as pressure upon the body of the wearer. The tests were made on a Dillon Tensometer equipped with a special proportional beam.

TEST DATA

Tip Type	Sample No.	Compressive Force Required For End Deflection	
		At 45° to Axis, lbs.	At 90° to Axis, lbs.
Polyethylene	1	0.5	1.17
	2	0.5	1.33
	3	0.42	1.00
	4	0.42	1.00
	5	0.47	1.00
Average		0.46	1.10
Metal Cap	1	1.2	3.7
	2	1.7	3.3
	3	1.5	2.7
	4	1.3	3.0
	5	2.0	3.2
Average		1.6	3.3

from which it is apparent that the resistance of the metal

capped boning is several times higher than that of the capped polyethylene tips.

It should be noted that the lower portion 28 of terminal or tip 26 bows outwardly or is convex on opposed sides creating a wider cross-sectional area than the upper portion 27, thus providing a greater degree of rigidity from about its center portion to its inner or attached end than from its center portion to its outer or free end. The lower portion 28 is also strengthened by the upper end of the wire 20' fortifying the strength and rigidity of the lower portion 28. The upper extreme end 27 of terminal or tip 26 is rounded both laterally and endwise, as seen in Figs. 1 and 2 at numerals 29, 30, respectively, for greater ease and comfort to the wearer of the garment. The opposed faces of terminal 26 slope gradually laterally and longitudinally towards the outer edges, as shown in Figs. 2 and 6.

In using the boning with terminal 26, the garment pocket 22, and the boning therein, extends to practically the very ends of the garment pocket, that is to edges 24 so that the upper portion 27 also lies within the border space between stitching 25 and edge 24. Thus, the sewing machine needle sews right through the soft, flexible plastic without losing speed or breaking of the needle. Not only is the boning held within the garment pocket itself but its terminals 26 are also fixed in lateral immovable position by stitching 25 passing therethrough. This also applies to the opposed terminals 26.

Fig. 3 shows the same terminals 26 shown in Figs. 1 and 2, except that said terminals are molded thereon on the opposed ends upon a spiral flattened wire, known in the industry, instead of the serpentine wire 20' shown in Fig. 1.

Fig. 4 also shows the same opposed terminals shown in Figs. 1, 2, and 3, except that such terminals are molded upon flat steel stays, also known in the industry.

Figs. 5 and 6 show a modified terminal 31 which is of approximately the same configuration as that shown in Figs. 1 and 2, except that there is a channel 32 in the lower portion, approximately one-half the length of the terminal for the purpose of receiving the ends of the stay, whether it be bent wire or flat steel. Terminal 31

may be attached to the wire or flat steel by a suitable adhesive placed in channel 32 or by the application of heat and pressure.

Another feature of my plastic cap or terminal is the permanence of the plastic cap attachment which makes separation from the boning an impossibility. In the case of crimped metal caps, these can separate and move away from the boning end within the garment tunnel thus exposing the dangerous raw cut boning ends.

It is obvious that various changes and modifications may be made in the details of construction and arrangement of form and parts without departing from the general spirit of the invention.

I claim:

15 A garment boning comprising an elongated relatively wide and flat flexible metallic member having a terminal at one end thereof, said terminal being of resilient plastic material readily pierceable by a sewing machine needle, said terminal being of substantial width and length and having opposed side faces and a marginal edge, the inner portion of said terminal embracing and being attached to said one end of said metallic member and contributing a substantial degree of rigidity and strength thereto, the outer portion of said terminal extending beyond said end of the metallic member and being free and flexible under body pressure, and said opposite side faces of the terminal being convex.
